[57] CLAIM

The ornamental design for a motorized skate board with seat, as shown and described.

DESCRIPTION

FIG. 1 is a perspective view of a motorized skateboard with seat showing my new design;

FIG. 2 is a left side elevational view thereof;

FIG. 3 is a right side elevational view thereof;

FIG. 4 is a front elevational view thereof;

FIG. 5 is a rear elevational view thereof; and,

FIG. 6 is a top plan view thereof.

The surface(s) or portion(s) of the article not shown in the drawing or described in the specification form(s) no part of the claimed design.
